CLAIM

The ornamental design for an arrhythmia monitor, as shown and described.

DESCRIPTION

FIG. 1 is a front, bottom, and left-side perspective view of an arrhythmia monitor showing my new design.

FIG. 2 is a front, bottom, and right-side perspective view of the arrhythmia monitor of FIG. 1.

FIG. 3 is a rear, bottom, and right-side perspective view of the arrhythmia monitor of FIG. 1.

FIG. 4 is a front view of the arrhythmia monitor of FIG. 1.

FIG. 5 is a rear view of the arrhythmia monitor of FIG. 1.

FIG. 6 is a left-side view of the arrhythmia monitor of FIG. 1.

FIG. 7 is a right-side view of the arrhythmia monitor of FIG. 1.

FIG. 8 is a top view of the arrhythmia monitor of FIG. 1; and,

FIG. 9 is a bottom view of the arrhythmia monitor of FIG. 1.

1 Claim, 8 Drawing Sheets
